MOVING STAIRWAY

James Dunlop, Park Ridge, Ill., assignor to
Westinghouse Electric Elevator Company,
Chicago, Ill., a corporation of Illinois

Application June 26, 1937, Serial No. 150,492

3 Claims. (Cl. 198—16)

My invention relates to moving stairways and more particularly to the steps embodied therein.

My application Serial No. 198,867, filed March 30, 1938, is a division of this application.

One object of my invention is to provide a moving stairway step which shall be simple and economical to manufacture and which shall be quiet and easily maintained in operation under varying conditions.

Another object is to provide a stairway step having a very small number of structural parts in its structure.

Another object is to provide a moving stairway step in which the riser or apron will serve not only as an apron but will also serve as a support for the tread of the step and maintain its correct shape without the use of a step frame.

A further object is to provide for obtaining quietness in the operation of moving stairway steps when they are traveling without any load as well as when they are traveling with a load.

A further object is to provide for absorbing the vibrations of a moving stairway step in one manner when it is traveling under no load and for absorbing the vibrations of the step in another manner when it is traveling under a load.

It is also an object to provide for the automatic transfer of the step from one vibration preventing means to the other vibration preventing means when the load condition of the step changes.

For a better understanding of the invention, reference may be had to the accompanying drawing, in which:

Figure 1 is a top plan view of a step for a moving stairway;

Fig. 2 is a view in rear elevation, partly in section, of the step shown in Fig. 1;

Fig. 3 is a view in right-hand end elevation of the step shown in Fig. 1;

Fig. 4 is a view, taken from the interior of the step, of the riser or apron of the step;

Fig. 5 is a view in end elevation of the apron or riser illustrated in Fig. 4;

Fig. 6 is an enlarged representation of the left-hand front axle bearing of the step illustrated in Fig. 2;

Fig. 7 is an enlarged view in end elevation of the lower portion of Fig. 5; and

Fig. 8 is an enlarged view, in section, of the lower left-hand portion of Fig. 3 showing the joint between the lower end of the step riser and the yoke on which it is secured.

Referring more particularly to the drawing, I have illustrated a moving stairway step as comprising a step tread 10, an apron or riser 11, a pair

of end bars 12 and 13, a pair of leading rollers 14 and 15 and a pair of trailing rollers 16 and 17.

The step tread 10 may be constructed of any suitable material, preferably of molded fibrous material, with a heat hardened binder, and it may be constructed in a plurality of sections or in one complete section provided with a plurality of cleats 19 disposed on its upper surface to provide a plurality of grooves 20. The tread is supported upon the upper edge of the riser 11 and an angle iron 22, which extends from the end bar 12 to the end bar 13. The underside of the tread is provided with a groove 23 which engages the angle iron 22 to prevent the tread from working forward or backward. The angle iron is supported in position by securing one end to a bracket 24 on the upper portion of the end bar 13 by suitable bolts 25. The other end of the angle iron is secured in a like manner to a bracket 26 on the upper portion of the end bar 12. The lower ends 20 of the bars 12 and 13 are provided with suitable brackets 27 and 28 for supporting the lower edge of the apron 11.

Heretofore in constructing moving stairway steps, it has been customary to provide a step frame comprising a plurality of bars and brackets bolted or melted together, but in practicing my invention, I provide an improved construction which eliminates a considerable amount of the vibration usually inherent in a step structure of many parts. This is accomplished by providing improved bearing supports and by eliminating part of the step frame and substituting therefor an improved form of riser which acts as a portion of the step frame and as an apron for the step.

As shown in Figs. 4 and 5, the apron 11 comprises a sheet 30, preferably of stainless steel, bent into a slight upward curve and having its upper edge 31, its lower edge 32 and its end edges 33 and 34 bent inwardly substantially at right angles to the face of the riser. The bent in end portions 33 and 34 provide a strengthening angle at each end for the riser plate so that it will be able to support the step tread 10 without bending. The upper bent in edge 31 is provided with small upwardly extruded portions 36 disposed to enter a groove 37 in the underside of the tread 10 to assist in holding the tread in its correct position.

A tapped bar 38 is spot welded, as at points 39, to the underside of the bent in edge 31 to act as a stiffening bar and to also provide a plurality of tap holes 41 disposed to receive a plurality of screws 42 which pass through the tread 10 and hold it in position on the riser 11. A lug 43 is disposed on the inturned edge 32 of the riser at the left-hand

end (Fig. 4), and a lug 44 is disposed on the in-turned edge 32 at the right-hand end of the riser. These lugs are spot welded to the in-turned edge and are provided with bolt holes 45 and 46 by 5 means of which they may be firmly bolted to the cooperating lugs 27 and 28 on the end bars 12 and 13. The in-turned edge 32 is also provided with downwardly extruded portions 48 and 49 disposed to be seated in cooperating grooves 50 in the 10 brackets 27 and 28, respectively, at the lower ends of the bars 12 and 13 to aid in maintaining the riser plate in its correct position on the end bars.

The lower edge of the riser plate is protected by a guard plate 53 which extends along the central 15 portion of the in-turned edge 32 and is securely riveted thereto by a plurality of rivets 54. The outer edge 55 of the guard plate 53 is bent downwardly to protect and complete the outer face of the riser 11.

20 By this construction, it will be seen that the step tread 10, the riser 11, the angle iron 22 and the end bars 12 and 13 are secured in such a manner as to provide a complete step structure of relatively few parts and yet a structure which 25 is strongly and firmly held together by a small number of screws and bolts. It will also be seen that the smaller number of parts held together will reduce the amount of vibration in the step and thereby eliminate a source of noise usually 30 present in the operation of moving stairways.

Referring to the rollers on the step, the leading roller 14 is mounted upon the outer end of a front axle 60 and is held in position thereon by a nut 61. The axle is mounted in an axle support 57 on 35 the front or upper portion of the end bar 12 and in an axle support bracket 62 attached to the cross angle iron 22 by a bolt 63. The axle is held in the brackets 57 and 62 by resilient bushings 64, preferably of rubber or similar material. A 40 cotter pin 65 is disposed through a collar 66 on the axle 60 to prevent its movement to the left, and a similar cotter pin 67 and collar 68 are disposed adjacent to the bracket 62 to prevent the axle from moving to the right. The leading roller 45 15 at the right is mounted in the same manner as the leading roller just described.

The trailing roller 16 is rotatably mounted upon the outer end of a stub axle 71 and is secured thereon by a suitable nut 72. The stub axle is 50 mounted in the trailing axle support 73 by means of a resilient sleeve 64a which is retained in position by a pair of suitable washers 74 and 75. A nut 76 on the inner end of the stub axle holds the combination firmly in position. The trailing 55 roller 17 is mounted upon a stub axle disposed in the trailing roller support 78 in the same manner as the stub axle for the trailing roller 16 is mounted in its support.

In the steps heretofore constructed, the resilient bushing 64 has been constructed usually of a solid resilient material, but in practicing my invention I provide a resilient bushing having two different surfaces for supporting the step in order to decrease its vibration and enable it to be operated without the noise that usually accompanies moving stairway steps. By referring to Fig. 6, it will be seen that the bushing 64 is provided with a no-load bearing surface comprising a pair of narrow circular ridges 80 and 81 extending 60 entirely around the bushing to engage the inner surface of the axle support bracket in which the bushing is mounted for the purpose of supporting the step while it is operating without load. The bushing is also provided with a load bearing surface 70 face 82 of less diameter than the no-load surface

and which is disposed to receive and support the axle support bracket when the step is carrying a load such as that of a passenger. A groove 83 is disposed at each side of each of the ridges 80 and 81 to provide room for the ridge of resilient material to spread or flow into when a load on the step bears the bracket downwardly to where it engages the load bearing surface 82. The bushing is also provided with a beveled end 85 to enable it to be easily positioned in the bracket 10 during the assembling of the step parts. A shoulder 87 is disposed on the other end of the bushing to provide a seat for the collar 66 through which the cotter pin 65 passes. Each axle support bracket is provided with a similar bushing, 15 and it will be apparent that when the step is running with no load, the ridges 80 and 81 on each of the bushings will support the bracket on their thin outer faces and that the tendency for the step to vibrate in a disturbing manner will be 20 eliminated by reason of the light resilient support on which it rests. It will also be apparent that when the step is loaded, as by a passenger standing thereon, the weight of the load will cause the brackets to overcome the slight resilient support 25 of the ridges 80 and 81 and move down to rest upon the face 82 of the central portion of the bushing, and that in this position the loaded step will be firmly but resiliently supported in such manner that practically all vibration because of 30 its loaded condition will be eliminated, and, therefore, that the step will operate quietly and without any disturbing noise.

Although I have illustrated and described only one moving stairway step embodying my invention, it will be obvious that many changes and modifications may be made therein without departing from the spirit and scope of the invention.

I claim as my invention:

1. A moving stairway step comprising a pair of 40 end bars, a cross member connecting the front ends of the end bars, a curved sheet metal riser having its edges bent inwardly to a position substantially at right angles to its body, a brace bar secured to the inner upper surface of the lower 45 bent-in edge of the riser, a metal bar secured to the inner face of the upper in-turned edge of the riser, means connecting the lower edge of the riser to the rear ends of the end bars, a step tread, means for mounting the step tread with its 50 front portion on the cross member and its rear portion supported solely on the riser, a plurality of rollers, and means for attaching the rollers to the end bars to support the step on a track.

2. A moving stairway step comprising a pair of 55 end bars, a cross member connecting the front ends of the end bars, a curved sheet metal riser having its edges bent inwardly to a position substantially at right angles to its body, a brace bar secured to the inner upper surface of the lower 60 bent-in edge of the riser, a metal bar secured to the inner face of the upper in-turned edge of the riser, means connecting the lower edge of the riser to the rear ends of the end bars, a step tread, means for mounting the step tread with its front 65 portion on the cross member and its rear portion supported solely on the riser, a plurality of rollers, means for attaching the rollers to the end bars to support the step on a track, and a downwardly extending protecting strip of metal secured to the 70 lower in-turned edge of the riser.

3. A step for a moving stairway comprising a pair of end bars, a cross member connecting the front ends of the end bars, a sheet metal riser connecting the rear portions of the end bars, said 75

riser having its end edges bent inwardly to stiffen it vertically for preventing buckling and having its lower edge turned inwardly to provide a surface to engage the rear portions of the end bars 5 and a short portion of its upper edge turned inwardly to provide a seat for a step tread and its upper bent-in edge having upwardly extruded portions, and a step tread having its front portion removably secured to the cross member and 10 its rear portion removably secured to the upper edge of the riser and having indentations in the underside of its rear portion to fit over the ex-

truded portions on the upper edge of the riser to prevent relative movement of the tread and the upper edge of the riser when they are engaged with each other, whereby the only direct connection between the upper edge of the riser and the 5 front ends of the cross member is the step tread, and removal of the step tread from the cross member and the riser permits entry to the interior of the stairway with no material interposed between the upper edge of the riser and the cross 10 member.

JAMES DUNLOP.
